UNITED STATES PATENT OFFICE.

FRED A. WRIGHT, OF WILMINGTON, NORTH CAROLINA.

FRAMEWORK FOR REINFORCING AND SHAPING CONCRETE STRUCTURES.

1,336,547.

Specification of Letters Patent. Patented Apr. 13, 1920.

Application filed February 21, 1919. Serial No. 278,473.

To all whom it may concern:

Be it known that I, FRED A. WRIGHT, a citizen of the United States, residing at Wilmington, in the county of New Hanover, State of North Carolina, have invented certain new and useful Improvements in Framework for Reinforcing and Shaping Concrete Structures, of which the following is a description, reference being had to the accompanying drawing and to the figures of reference marked thereon.

The invention relates to new and useful improvements in a framework for reinforcing and shaping concrete structures and more particularly to a structure of this character which may be used in the building of ships, freight cars, silos, or the like.

An object of the invention is to provide a framework of the above character which is made up of vertically extending and horizontally extending frame parts, which contain means within themselves for interlocking the frames, so that the framework may be set up without the use of bolts, angle 25 plates or the like.

A further object of the invention is to provide a frame structure of the above character, wherein the vertically extending and horizontally extending frame parts are formed of V-shaped angle bars which may be readily bent to conform to the contour 30 of the construction which it is desired to build.

A further object of the invention is to provide a frame structure of the above character with vertically extending and horizontally extending reinforcing rods which are connected to the frame parts by recessing said frame parts and using a locking 35 means common to a plurality of the rods, whereby the structure may be assembled without the use of bolts or rivets and from bars, rods and wires of the usual commercial form.

A still further object of the invention is to provide a construction of the above character, wherein fabricated metal is secured to the reinforcing rods by metal clips, which 40 fabricated metal forms spaced walls between which the concrete is poured and through which the concrete passes to a limited extent, thus forming and shaping the concrete structure and at the same time embedding not only the frame structure but 45 the fabricated metal, within the surfaces of the concrete structure.

These and other objects will in part be obvious and will in part be hereinafter more fully disclosed.

In the drawings, which show by way of 60 illustration one embodiment of the invention,

Figure 1 is a view in vertical section, showing the united framework, rods and fabricated metal and also showing a portion of the finished concrete wall, with these parts embedded therein;

Fig. 2 is a plan view of a ~~viewed~~ frame, from which one of the V-shaped angle bars or frames, is formed;

Fig. 3 is a similar view of the other angle bar or frame;

Fig. 4 is a plan view, showing the frames, rods and fabricated metal assembled ready for the pouring of the concrete;

Fig. 5 is a perspective view of one of the 75 clips for holding the fabricated metal to the rods; and

Fig. 6 is a similar view, but showing in dotted lines the rod and the clip as bent for holding the metal.

The invention broadly consists in a framework for reinforcing and shaping concrete structures, whereby the concrete structure may be built without the use of 85 shaping molds of any character. To this end, the framework is formed of horizontally and transversely extending bars which are joined together by interlocking means formed as a part of the bars, so that no 90 bolts, rivets, or the like are necessary for the securing together of these angle bars. The angle bars are in long lengths and are cold bent or shaped to conform to the contour of the construction which it is desired 95 to build. After these angle bars have been placed, then reinforcing rods are attached to the angle bars. These reinforcing rods are preferably set in recesses formed in the angle bars and secured thereto by locking 100 wires so that in the assembling of the reinforcing rods no bolts or rivets are necessary and these rods will bend to conform to the shape of the bars to which they are attached. The rods are placed adjacent the 105 outer edges of the bars and an expanded fabricated metal is secured to the rods at one side of the framework while an expanded fabricated metal is secured to the rods at the other side of said framework. This 110 forms two spaced walls of fabricated metal between which the concrete is poured. The

concrete passes out through the openings in the expanded metal to a certain extent, so that the entire frame structure, including the expanded metal, is keyed together and 5 embedded in the concrete structure. A concrete gun is then used to face the inner and outer walls. This completes the structure.

The invention will perhaps be more clearly understood by a brief reference to the drawings, wherein I have shown my improved 10 framework as consisting of vertically and horizontally extending angle bars or frames, which are somewhat similar in construction. The vertical bars are indicated at 1 in the drawings. These vertical bars are punched 15 from a blank which is shown in Fig. 3 of the drawings, said blank having closely spaced notches 2, at each edge thereof. The blank is adapted to be bent on the broken 20 line x, x , of Fig. 3, to form an angle bar.

For the purpose of description, I am referring to the part of the bar where it is bent and where the side walls of the bar 25 meet, as the vertex of the bar, and the free edges which have the notches, as the base of the bar.

At the vertex of the bar are notches or 30 cut-away portions 4, which are inclined to the longitudinal axis of the bar and these notches or cut-away portions are adapted to 35 receive rods, as will be hereinafter more fully described. The horizontal frames or bars are formed from blanks as indicated at 3 in Fig. 2. These blanks are formed at each 40 side with pairs of notches 5, 5, which are oppositely inclined to the edge of the blank. This blank is adapted to be bent on the broken line x, x , to form an angle bar similar in shape to the angle bar 1.

40 The angle bar forming the horizontal member is made with a notch or cut-away portion 6 similar to the notch or cut-away portion 4, except that it extends at right angles to the longitudinal axis of the bar. 45 All the bars, both the vertical and horizontal, are formed with openings 7, which may be of any desired shape. The purpose of these openings is to receive the concrete, so that the bars will be firmly anchored in the solid 50 concrete walls, by the concrete keys which are formed in these openings. This prevents the bars from sliding endwise in the concrete.

These angle bars come in long lengths 55 and may be said to be of commercial form. The bars are placed preferably about three feet apart, both vertically and horizontally, although this may be varied according to the structure which is being made. The vertical 60 bars are bent to conform to the shape or contour of the construction which is being built, as for example, if the framework is being used to form a ship, then the vertically extending angle bars are shaped to conform 65 to the contour of the ship in vertical cross

section. If a silo is being formed, then the bars will be shaped to conform to the vertical cross section of the silo. The horizontal V-shaped angle bars are also bent to conform in shape to the horizontal cross section of 70 the ship, or to the silo.

As above noted, these bars come in long 75 lengths of sixty feet or the like, and the end of one bar may be readily attached to another by the use of suitable devices which will bend portions of one bar into the other; or said bars may be spot welded or connected in any other way which avoids the use of bolts or rivets and requires more or less expert labor.

80 The horizontal and vertical bars are connected at their intersecting points by the springing of the edges at the base of the vertical bar into the pairs of notches 5, 5 in the horizontal bars. The edges of the V-shaped bar which engage the notches 5, 5, are preferably curved outwardly slightly so as to assist in retaining the bars in interlocked relation.

85 Of course, it will be understood that the vertical bar may have the pairs of notches instead of the horizontal bar. The notches 2, 2 in the vertical bar coming against the outer faces of the side members of the horizontal bar, will prevent the bars from moving 90 endwise in the notches 5, 5 and thus the vertical and horizontal bars will be firmly locked together by interlocking means, which is a part of the bars themselves. Thus 95 it will be seen that this interlocking means 100 is free from bolts or rivets or any other special connecting devices, which require the use of expert labor in order to assemble the parts.

105 After these frames have been shaped and assembled, then vertically extending reinforcing rods 8 are attached to the horizontally extending bars 3. These rods are placed in the notches or cut-away portions 6 and the notches or cut-away portions 6 are 110 of sufficient depth to receive the rod and permit a wire 9 to be passed along inside of the horizontal angle bar 3 at the vertex thereof and between the inner wall of the angle bar and the rod 8.

115 It will be understood that these wires are in long lengths and a series of rods are placed in the notches and the wire pushed along behind first one rod after another. The notches 6 which receive the rods are 120 preferably spaced on two-inch centers and rods may be placed in each notch or in every other notch, or in every third notch, according to the particular construction which is being formed and the desired number of reinforcing rods which should be used.

125 Horizontally extending reinforcing rods 10 are inserted in the inclined notches or cut-away portions 4 of the vertically extending angle bars 1. In placing these vertically 130

extending angle bars, they are set so that the notches or cut-away portions 4 incline downwardly and thus the rods will be held by gravity in the notches temporarily. The 5 notches are of sufficient depth so a locking wire 11 similar to the locking wire 9 may be used for holding these rods 10 in place. These notches or cut-away portions 4 are spaced similar to the notches in the cut-away 10 portions 6 and rods may be placed in every notch or every other notch or in any other way according to the desired number of reinforcing rods that are to be used.

After the frame and the reinforcing rods 15 have been assembled, then an expanded fabricated metal 12, which may also be of commercial form, is attached to the vertically extending rods at their outer faces and an expanded fabricated metal 13 is secured to 20 the outer faces of the vertically extending reinforcing rods. As a means for securing the fabricated metal in place, I have provided a clip 14 which is U-shaped and has projecting prongs 15, 15. This clip is placed 25 around the rod, as clearly shown in Fig. 6 of the drawings and bent to conform to the shape of the rod, bringing the prongs closely together. The prongs 15 are extended through one of the openings in the expanded 30 fabricated metal and then the ends 16 are bent laterally, so as to firmly hold the fabricated metal in place against the rods. These clips also hold the fabricated metal against the extreme outer edges of the vertical and 35 horizontal frame members.

After the expanded fabricated metal has 40 been attached to the rods and frame members, thus forming spaced vertical walls, concrete is poured between the walls, entirely filling the space between such walls. The concrete as it is poured, will pass 45 through the openings in the fabricated metal, thus making a key which firmly secures the fabricated metal to the frame structure and in part embeds the fabricated metal in the concrete. A concrete gun may then be used to face up the inner and outer walls and this completes the structure.

In the completed structure the vertical 50 and horizontal members, reinforcing rods and expanded fabricated metal, are all embedded in the concrete and firmly united and keyed together, so that a solid wall of concrete thoroughly reinforced is formed and this is formed without the use of any shaping molds of any character.

It will further be noted that in the setting up of the frame structure, no bolts or rivets of any character are used and the 60 frame structure is built almost wholly from parts of a commercial form. The structure may, therefore, be quickly built at little expense and without the use of expert labor.

It will be obvious that minor changes in 65 the details of construction and the arrange-

ment of parts may be made, without departing from the spirit of the invention as set forth in the appended claims.

Having thus described my invention, what I claim as new and desire to secure by Letters Patent, is:—

1. A framework for reinforcing and shaping a concrete structure including in combination, a series of transversely and vertically extending frame members shaped to 75 conform to the contour of said structure and having interlocking means at their points of intersection for securing the same together, a series of reinforcing rods secured to said frame members and lying respectively adjacent the outer faces thereof, expanded fabricated metal secured to the reinforcing rods and forming spaced walls, whereby concrete may be poured between said walls, filling the space therebetween 80 and extending through the openings in the fabricated metal, thus forming a keyed solid concrete wall, conforming in shape to the frames and reinforcing rods.

2. A framework for reinforcing and shaping a concrete structure including in combination, a series of longitudinally extending frame members shaped to conform to the contour of the structure, a series of transversely extending frame members shaped to 90 conform to the contour of the structure, said frame members being V-shaped in cross section with the bases of the frame members in contact, the frame members of one of said series having notches into which the edges 100 of the other frame member may be sprung, whereby the frame members are locked together, reinforcing rods secured to said frame members and lying respectively adjacent the outer faces thereof, and expanded 105 fabricated metal secured to the outer faces of the reinforcing rods, whereby concrete may be poured between the walls formed by the fabricated metal, filling the space therebetween and extending through the openings 110 in the fabricated metal, thus forming a keyed solid concrete wall conforming in shape to the frames and reinforcing rods.

3. A framework for reinforcing and shaping a concrete structure including in 115 combination, a series of longitudinally extending frame members shaped to conform to the contour of the structure, a series of transversely extending frame members shaped to conform to the contour of the 120 structure, said frame members being V-shaped in cross section with the bases of the frame members in contact, the frame members of one of said series having notches into which the edges of the other frame member 125 may be sprung, whereby the frame members are locked together, the frame members of the other series having notches to prevent endwise movement of the frame members on each other, reinforcing rods secured to said 130

frame members and lying respectively adjacent the outer faces thereof, and expanded fabricated metal secured to the outer faces of the reinforcing rods, whereby concrete 5 may be poured between the walls formed by the fabricated metal, filling the space therebetween and extending through the openings in the fabricated metal, thus forming a keyed solid concrete wall conforming in 10 shape to the frames and reinforcing rods.

4. A framework for reinforcing and shaping concrete structures including in combination, a series of longitudinally extending V-shaped bars, a series of transversely extending V-shaped bars, the free edges of one of said series of bars having notches formed therein arranged to receive the free edges of the other series of bars, whereby said bars are locked together, and 15 reinforcing rods and expanded fabricated metal secured to said V-shaped bars opposite the free edges thereof.

5. A framework for reinforcing and shaping a concrete structure including in combination, a series of longitudinally extending and V-shaped bars, a series of transversely extending V-shaped bars, the free edges of one of said series of bars having notches formed therein arranged in pairs to 20 receive the free edges of the other series of bars, whereby said bars are locked together, said bars having notches formed therein at their vertices in which are adapted to be placed reinforcing rods, wires located within 25 the angle bars and engaging the outer faces of the reinforcing rods for holding the same in place.

6. A framework for reinforcing and shaping a concrete structure including in combination, a series of longitudinally extending and V-shaped bars, a series of transversely extending V-shaped bars, the free edges of one of said series of bars having notches formed therein arranged in pairs to 30 receive the free edges of the other series of bars, whereby said bars are locked together, said bars having notches formed therein at their vertices in which are adapted to be placed reinforcing rods, wires located within 35 the angle bars and engaging the outer faces of the reinforcing rods for holding the same in place, clips secured to said reinforcing bars, and expanded fabricated metal secured by said clips to the outer faces of the rods, 40 thus forming spaced walls between which concrete may be poured.

7. A framework for reinforcing and shaping a concrete structure including in combination, a series of longitudinally and vertically extending V-shaped bars having their 45 free edges interlocked said bars having notches formed at their vertices adapted to receive reinforcing rods, said notches being of sufficient extent to permit a locking wire

placed with the angle bar to hold the rods in 65 the notches.

8. A framework for reinforcing and shaping a concrete structure including in combination, a series of longitudinally and vertically extending V-shaped bars having their 70 free edges interlocked, said bars having notches formed at their vertices adapted to receive reinforcing rods, said notches being of sufficient extent to permit a locking wire placed within the angle bar to hold the rods 75 in the notches, the notches in said vertical bars being inclined downwardly for holding the rods in place until the wires are inserted.

9. A framework for reinforcing and shaping a concrete structure including in combination, a series of intersecting V-shaped bars having their free edges slotted to provide an interlocking connection, said bars having notches formed at their vertices adapted to receive reinforcing rods, said 80 notches being of sufficient extent to permit a locking wire placed within the angle bar to hold the rods in the notches.

10. A framework for reinforcing and shaping a concrete structure including in combination, a series of longitudinally and vertically extending V-shaped bars having their free edges secured together, said bars having notches formed at their vertices adapted to receive reinforcing rods, said 90 notches being of sufficient extent to permit a locking wire placed within the angle bar to hold the rods in the notches, the notches in said vertical bars being inclined downwardly for holding the rods in place until 100 the wires are inserted, means for securing an expanded fabricated metal to the outer faces of the reinforcing rods, thus forming spaced walls between which concrete may be poured, said V-shaped bars having openings 105 formed therein for receiving the concrete, so that said V-shaped bars are keyed and held from endwise movement in the concrete.

11. A framework for reinforcing and shaping a concrete structure including in combination, a series of longitudinally extending V-shaped bars shaped to conform to the contour of the structure, a series of transversely extending V-shaped bars shaped to conform to the contour of the 110 structure, the free edges of one of the said series of bars having pairs of notches formed therein inclined outwardly away from each other, the free edges of the other series of bars being curved outwardly and adapted to 115 engage the pairs of notches for locking said bars together.

In testimony whereof, I affix my signature, in the presence of two witnesses.
